UNITED STATES PATENT OFFICE

91,819

DESIGN FOR A WALL VANITY

Lurelle Guild, Darien, Conn., assignor to C. F. Church Mfg. Co., Holyoke, Mass., a corporation of Massachusetts

Application August 26, 1933, Serial No. 49,136

Term of patent 7 years

all whom it may concern:

Be it known that I, LURELLE GUILD, a citizen of the United States, residing at Darien, in the County of Fairfield and State of Connecticut, have invented a new, original and ornamental design for a Wall Vanity, of which the following specification, reference being had to the accompanying drawing, forming part thereof.

The figure is a perspective view of a wall vanity showing my new design.

I claim:

The ornamental design for a wall vanity, substantially as shown.

LURELLE GUILD.
